ATTORNEY

UNITED STATES PATENT OFFICE.

FARMLY H. RYDER AND CHARLES W. MOORE, OF BUCYRUS, OHIO, ASSIGNEES TO
SMOKELESS OIL BURNER COMPANY, A CORPORATION OF OHIO.

OIL BURNER.

Application filed June 22, 1922. Serial No. 570,198.

This invention relates to improvements in oil burners and method of operating the same.

An object of the invention is the provision of an oil burner in which the fuel supply is automatically controlled once the burner is set in operation.

Another object is the provision of an oil burner having means for regulating the operating pressure of the atomizing steam, thereby effecting automatic control of the fuel supply with the consequent saving of fuel.

Another object of the invention is the provision of a burner having means whereby the fuel supply is automatically controlled by the pressure of the steam in a pipe line leading from a boiler which may be heated by the burner.

Another object is the provision of an oil burner in which the supply of fuel and atomizing agent is synchronously controlled, preferably through a unitary structure or mechanism.

A further object of the invention is the provision of a burner which may be manually set and thereafter automatically regulated.

A still further object of the invention is providing a method for controlling the temperature of a furnace or pressure of steam in a boiler through means, the operation of which is dependent upon the presence of a gas, which gas may be the steam produced by a burner embodying the controlling means.

Other objects of the invention, having to do with various features of construction and arrangement of parts, will manifest themselves upon a reading of the following description and appended claims.

In accordance with our invention there is provided a main burner body or casing for housing a piston carrying at its internal end or head a nozzle communicating with a supply of fuel through an intake manifold. A steam inlet opening into a pressure chamber surrounding the piston provides means, by effecting a closure of the atomizing orifice, for regulating the burner from a boiler, or the like, heated by the burner. As the steam pressure falls the atomizing orifice is gradually opened by suitable means,

such as a helical spring under compression, thereby permitting an increased quantity 55 of the fuel to be atomized with a consequent rise in the steam pressure. Means are provided for manually setting the burner in such a manner as to define the range under which automatic regulation may be had. 60

The nature of the means by which the foregoing and other special objects of the invention are accomplished, will appear from the following detailed description.

Referring to the drawings, 65 Fig. 1 is a longitudinal section of a burner embodying the invention;

Fig. 2 is a cross section, taken on line II—II of Fig. 1; and

Fig. 3 is a rear end view. 70

Like reference characters refer to like parts throughout the several figures.

The burner illustrated in the accompanying drawings comprises a casing 1 having reciprocally mounted therein a piston 2. The 75 interior of the casing is provided with what may be termed a pressure chamber 3 and a steam chamber 4, the function of which chambers will hereinafter be more fully described. The piston 2 comprises a cylindrical body portion provided on its forward end with an enlargement or head having substantially centrally disposed radial openings extending from the axis of the piston into a fuel chamber 5. Extending from the 80 piston head is a hollow stem or shank portion 6 carrying a stop collar 7 and provided at its extremity with an external threaded portion 8. The fuel chamber 5 is formed in the piston head by making a centrally 85 located annular groove therein, thus substantially dividing the head into two sections 9 and 10. The forward end of the piston is provided with an internal thread into which is screwed a tapering nozzle 11 adapted to fit into a corresponding orifice provided in the casing 1 adjacent the steam chamber 4. The shank portion of the piston 90 2 is journaled in position by means of reduced stuffing nuts 12 and 13. A helical spring 14 is confined between the external end of the stuffing nut 13 and an adjusting nut 15 having screw-threaded engagement with the threaded portion of the piston shank 6. Section 9 of the piston head has a central recess which is threaded so as to

95

100

105

accommodate the threaded end of a needle point valve 16 carried upon the inner end of valve stem 17 which extends through a stuffing nut 18 and is provided with a handle 19. The nozzle 11 is provided with a central opening 21 which in conjunction with the centrally disposed radial openings constitutes a passageway to the oil chamber 5. The needle valve 16 is disposed to control the passageway from the oil chamber by means of the handle 19.

The pressure chamber 3 and steam chamber 4 are provided with ports 22 and 23, respectively, and are placed in communication 15 with each other by means of a passageway 24. The port 23 to the atomizing chamber 4 is controlled by a valve 25, the stem of which is suitably journaled in stuffing nut 26 and terminates in a handle 27. By means 20 of valve 25, port 23 of the steam chamber 4 may be controlled. The piston 2 is provided with rings 28 so as to make the chambers of the burner gas tight.

An oil inlet 29 and a steam inlet 30 are 25 provided at the top and bottom portions, respectively, of the casing 1. The oil inlet 29 is immediately over section 9 of the piston head and the steam inlet 30 communicates with the passageway 24 joining the steam 30 chamber 4 and steam pressure chamber 3. It is obvious that as the piston 2 recedes or moves inwardly, the oil inlet is placed in communication with the fuel chamber 5, and the supply of fuel permitted to flow through 35 the passageway 21 of the nozzle 11 may be controlled by handle 19 of the needle point valve 16. It is also obvious that the steam which may be admitted to the steam chamber through the port 23 may be regulated 40 by means of valve 25. By virtue of these adjustments it is possible to manually set the burner so as to employ any desired mixture of oil or other liquid fuel and steam or air during the operation of the burner. 45 To permit further adjustment of the burner I provide a boss 35 upon the exterior of the casing 1 and positioned immediately in front of the atomizing chamber 4. The boss 35 is threaded internally so as to receive a set screw 36 having a lock nut 37. By turning the screw inwardly the corresponding end thereof may constitute an abutment for arresting the further advancement of the piston 2 beyond a given forward position. 50 This arrangement makes it possible to prevent the burner from being completely shut off by the forward movement of the piston and, in effect, provides means for banking a fire under a boiler, etc., with which the burner 55 may be associated. It is obvious that the screw 36 may be rendered ineffective (as shown in the drawing) in the event that it is desired to permit the burner to be extinguished during the operation thereof.

60 65 The operation of the burner may be de-

scribed as follows. By means of the spring tension nut 15 the compression of spring 14 may be regulated so that a given head of steam or pressure in the chamber 3 is required to maintain closed the atomizing orifice of the steam chamber 4, which orifice is shown as closed in the drawing. The rearward movement of the piston 2 is limited by stop collar 7 coming in contact with the adjacent surface of the stuffing nut 12. It will, therefore, be seen that the travel of the piston is limited between a closed position to that in which the stop collar 7 engages with the stuffing nut 12. This travel, however, is sufficient to permit the full opening of the oil inlet 29 into the fuel chamber 5 and the atomizing port 23 into the steam chamber 4.

In starting the burner the valve 16 is adjusted to admit any quantity of fuel desired when the fuel inlet 29 is completely opened. The adjustment of the valve 25 is such that a proper amount of steam flows through the port 23 into the steam chamber and out through the atomizing orifice so as to give the desired mixture of steam and fuel when the burner is fully opened. With this adjustment as a maximum for a given condition the mixture of combustion materials is automatically regulated down to a point where it may be completely shut off by the closure of the atomizing orifice through the nozzle 11 engaging with the tapering wall of the casing 1 adjacent the orifice and the port 23 and oil inlet 29 by the piston sections 10 and 9, respectively.

As previously stated, the tension normally placed upon the spring 14 is determined by the maximum steam pressure which will be carried in the chamber 3. Naturally, the greater this pressure the more will the spring 14 be placed under compression when the piston is in normal position so as to offer more resistance to its movement in a forward direction. Suitable adjustments having been made of the nut 15 and valves 16 and 25, the fuel and steam are turned on. For starting purposes steam from an auxiliary source or separate system, or compressed air, may be used until a pressure has been obtained in the steam boiler served by the 115 burner, after which time the auxiliary supply may be discontinued in any suitable manner and steam from the controlled system substituted therefor.

When the burner is first started the piston under the influence of spring 14 will have receded, permitting the free passage of the oil and steam through the opening 21 and atomizing orifice of the chamber 4, respectively. Consequently, maximum combustion will be had until an increased pressure in the steam chamber 3 overcomes an increment of the resistance offered by the spring 14, thus effecting a slight closure of the atomizing chamber with a resulting decrease in 130

the intensity of the heat produced by the burner. It is, of course, to be appreciated that the steam line connected with the inlet 30 is either directly in communication with the boiler being heated by the burner or with an auxiliary source of supply which is directly influenced by the pressure of the steam in the boiler with which the burner is used.

As the steam pressure is further increased in the boiler there will be a corresponding increase of steam pressure in the chamber 3 of the burner. This increased pressure will further overcome the resistance of spring 14 and thus effect a further closure of the fuel inlet 29 and atomizing orifice of the chamber 4. As long as the piston continues to move forward due to an increase in the pressure of steam within the chamber 3, there will be a gradual cutting off of the combustion materials until they are completely shut off through the closure of the fuel inlet 29 and the port 23 by sections 9 and 10, respectively, of the piston. However, if the set screw 36 has been set to function the burner will never become entirely extinguished of itself. When the intensity of the burner is lowered there will be a gradual fall in the steam pressure within the boiler and a constant lowering of the pressure within the chamber 3. This lowering of steam pressure will permit the spring 14 to function thereby again opening the fuel inlet 29 and port 23. This will revitalize the burner and produce another gradual increase in the steam pressure, which in turn will eventually again effect the shutting down of the burner. This cycle of operation will continue as long as the burner is running.

From the foregoing it is obvious that by making the proper adjustments in the component parts of the burner a very delicate control may be obtained of the steam pressure in a boiler. The inter-dependence of action between the boiler and the burner makes it possible to obtain very close regulation of both the boiler and the burner with a consequent saving in fuel. This may be of particular advantage if the burner is used in connection with a heating plant since it is possible to maintain a uniform temperature in a building heated by a plant controlled by one or more of our burners. There are other features of advantage which are inherent in a burner embodying our invention, which advantages will be apparent to those skilled in the art.

While the invention has been described with reference to the special embodiment shown, it is obvious that various changes in detail may be made without departing from the spirit and scope thereof, but all such changes are desired to be regarded as contemplated by the invention as defined in the appended claims.

Where the term steam is used in the specification and appended claims, it is wished to be understood as including air as well, and that as used herein it is interchangeable with the word air.

What is claimed is:

1. In an oil burner the combination with a casing, a piston having a head movable within said casing, a pressure chamber and a steam chamber separated by said head, means for supplying steam to said chambers, a fuel inlet in said casing, a fuel outlet nozzle in said head, means for normally maintaining said inlet and outlet in communication, said piston being operable to cut off said communication when a predetermined pressure is created in said pressure chamber.

2. In an oil burner the combination with a casing, a piston having a head movable within said casing, a pressure chamber and a steam chamber separated by said head, means for supplying steam to said chambers, a fuel inlet in said casing, a fuel outlet nozzle in said head, a spring mounted on said piston to normally maintain said inlet and outlet in communication, said piston being operable to cut off said communication when a predetermined pressure is created in said pressure chamber.

3. In an oil burner the combination with a casing, a piston having a head movable within said casing, a pressure chamber and a steam chamber separated by said head, means for supplying steam to said chambers, a fuel inlet in said casing, a fuel outlet nozzle in said head, means for normally maintaining a communicating opening of a predetermined area between said inlet and outlet said piston being operable to vary the area of said opening upon a variation of pressure created in said pressure chamber.

4. In an oil burner the combination with a casing, a piston having a head movable within said casing, a pressure chamber and a steam chamber separated by said head, means for supplying steam to said chambers, a fuel inlet in said casing, a fuel outlet nozzle in said head, a spring mounted externally of said piston to normally maintain a communicating opening between said inlet and outlet and means for admitting a fluid under pressure to said pressure chamber to vary the effective area of said opening in accordance with the degree of pressure of said fluid.

5. In an oil burner the combination with a casing, a piston having a head movable in said casing, a compression chamber and a steam chamber, means for supplying steam to said chambers, a steam discharge orifice in said steam chamber, a fuel discharge nozzle carried by said head and movable therewith for varying the area of said orifice, a fuel inlet in said casing, a passage in said

- 4 head affording communication between said fuel discharge nozzle and said fuel inlet, means for normally effecting a predetermined discharge of fuel, said piston being movable for causing a variation in said fuel discharge in accordance with the degree of pressure in said pressure chamber.
- 5 6. An oil burner comprising a casing, a piston having a head movable in said casing, a steam chamber and a pressure chamber separated by said head, a communicating passage between said chambers, a valve for varying the area of said passage, a steam inlet to said passage, a discharge orifice in said steam chamber for the discharge of steam traveling through said passage, a member carried by said head for disposition in said orifice, said member having a passage therein for the discharge of fuel,
- 10 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880
7. An oil burner comprising a casing, a piston having a head movable in said casing, a steam chamber and a pressure chamber separated by said head, a communicating passage between said chambers, a valve for varying the area of said passage, a steam inlet to said passage, a discharge orifice in said steam chamber for the discharge of steam traveling through said passage, a member carried by said head for disposition in said orifice, a fuel discharge outlet in said head, a fuel inlet in said casing, a valve for varying the area of said fuel discharge outlet, means external of the casing for operating said valve, a spring mounted on said piston to normally maintain said fuel discharge outlet in communication with said fuel inlet and to maintain communication between said passage and said steam chamber, said head being movable under pressure created in said pressure chamber to cut off the fuel inlet and steam inlet to said steam chamber.
8. An oil burner comprising a casing, a piston having a head movable in said casing, a steam chamber and a pressure chamber separated by said head, a communicating passage between said chambers, a valve for varying the effective area of said passage, a steam inlet to said passage, a discharge orifice in said steam chamber for the discharge of steam traveling through said passage, a member carried by said head for disposition in said orifice, a fuel discharge outlet in said head, a fuel inlet in said casing, a valve for varying the area of said fuel discharge outlet, means external of the casing for operating said valve, a spring mounted on said piston to normally maintain said fuel discharge outlet in communication with said fuel inlet and to maintain communication between said passage and said steam chamber, said head being movable under pressure created in said pressure chamber to cut off the fuel inlet and steam inlet to said steam chamber, said head being movable under pressure created in said pressure chamber to cut off the fuel inlet and steam inlet to said steam chamber, and adjustable means for limiting the forward movement of said piston.
9. An oil burner comprising a casing, a piston having a head movable in said casing, a steam chamber and a pressure chamber separated by said head, a communicating passage between said chambers, a valve for varying the area of said passage, a steam inlet to said passage, a discharge orifice in said steam chamber for the discharge of steam traveling through said passage, a member carried by said head for disposition in said orifice, a fuel discharge outlet in said head, a fuel inlet in said casing, a valve for varying the area of said fuel discharge outlet, means external of the casing for operating said valve, a spring mounted on said piston to normally maintain said fuel discharge outlet in communication with said fuel inlet and to maintain communication between said passage and said steam chamber, said head being operable under pressure created in said pressure chamber to vary the area of the fuel inlet and the area of the steam inlet to said steam chamber in accordance with the pressure created in said pressure chamber, and adjustable means for limiting the forward movement of said piston.

In testimony whereof, we have hereunto subscribed our names this 19th day of June, 1922.

PARMY H. RYDER.
CHARLES W. MOORE.
